UNITED STATES PATENT OFFICE.

GEORGE F. WILLETT, OF DAYTON, OHIO.

FOLDING TABLE.

Application filed December 31, 1926. Serial No. 158,160.

This invention relates to folding tables and more particularly to that type of table commonly known as a card table in which the legs may be folded against the table top. Tables 5 of this type are necessarily of a very light construction so that they can be folded into a compact form and easily handled. In some instances the table legs are independently movable and each is moved separately into its 10 extended and folded positions. In other forms of table the several legs are connected one to the other so that they will be moved simultaneously into their extended or folded positions. In both forms of the table difficulty 15 has been experienced in so mounting the legs on the table top and bracing the same as to rigidly hold the legs in their extended positions and prevent the table from wobbling. In those tables in which the legs are connected 20 together for simultaneous movement further difficulty has been experienced in providing actuating means which would be efficient in operation and of a strong durable character without being heavy and cumbersome 25 or expensive of construction.

One object of the invention is to provide such a table with a very simple device for connecting the several legs one to the other, which will be of a strong durable character and of a 30 light compact construction.

A further object of the invention is to provide in connection with such an actuating device means for rigidly securing the legs in their extended positions.

35 A further object of the invention is to provide such a table with strong rigid pivotal support for the legs of such a character that the legs may be quickly and easily attached to the table top.

40 Other objects of the invention will appear as the device is described in detail.

In the accompanying drawings Fig. 1 is a bottom plan view of a table embodying my invention showing the legs in their folded positions; Fig. 2 is a sectional view taken on the line 2—2 of Fig. 1; Fig. 3 is a transverse sectional view of the table showing the legs in their extended positions; Fig. 4 is a bottom plan view of a portion of the table showing the 45 leg in its extended position; Fig. 5 is a detail sectional view showing the means for mounting the leg on the table top; Fig. 6 is a detail sectional view showing the lock and the means for releasing the same; Fig. 7 is a detail view 50 of the means for attaching the connecting bars with the actuating member; and Fig. 8 is a

sectional view showing the manner of mounting the actuating member on the table top.

In these drawings I have illustrated one embodiment of my invention and have shown 60 the same as applied to a table comprising a substantially square top, having at each edge thereof a depending flange 2. Pivotedly mounted at each corner of the table is a leg 3, each leg being mounted on an axis extending parallel with one of the flanges 2 so that the leg may be folded against the table top within and substantially parallel to an adjacent flange 2. The legs may be mounted on the table top in any suitable manner but 65 preferably each leg and its supporting structure is first assembled as a unit and this unit then secured to the table top. As here shown each leg is carried by a pin 4 which is supported at one end by a bracket 5 mounted 70 on one of the flanges 2 of the table top and has its other end mounted in a socket 6 in an adjacent flange 2. The bracket 5 comprises an apertured portion to receive the end of the pin and an attaching portion bent laterally, 75 as shown at 7, and extending beyond the inner end of the pin. The pin has its inner end reduced in diameter, as shown at 4^a to receive the apertured end of a brace bar 8, the other end of which is secured to the leg 3 at a point 80 spaced from the top thereof. The pin 4 has a second reduced portion 4^b to enter the apertured bracket. The end of the pin extends slightly beyond the bracket so that it may be upset or riveted to retain the bracket on 85 the reduced end portion thereof. The bracket being confined between the upset end of the pin and the intermediate reduced portion 4^a it will be apparent that it may be tightly riveted on the pin without binding the brace 90 95 8. In assembling the leg unit the leg and brace bar are first mounted on the respective ends of the pin and the bracket secured to the pin. The outer end of the pin is then inserted in the socket 6 and the bracket secured to the adjacent flange 2 in any suitable manner, as by means of screws 9. The arrangement of the attaching portion of the bracket is such that these screws may be easily inserted after the unit is in position. 100 If desired, the outer end portion of the pin, which extends through the leg may also be of reduced diameter and washers 10 interposed between the leg and the body portion of the pin and the flange in which the socket 6 is formed. It will be apparent that the leg 110 unit may be very quickly and easily assembled.

and then attached to the table top, thereby greatly facilitating the assembly of the table.

The several legs are connected one to the other in such a manner that the movement of 5 any one of the legs in either direction will cause a similar movement to be imparted to all the other legs, thus by grasping one leg and moving it to its extended position all the legs will be caused to move in unison to 10 their extended positions. Preferably this is accomplished by mounting beneath the table top an actuating device which is capable of rotatory movement in a plane substantially parallel with the table top. This actuating 15 member is supported in a series of guides spaced from the axis thereof and of such a character as to permit of the free rotatory movement of the actuating member, thus distributing the strains to which that member is 20 subjected between a number of guides or supporting members and avoiding the objectionable features which are present when an actuating device is mounted on a single pivot at its center, which usually results in the pivot 25 becoming loose and thus destroying the operative connection between the legs. This actuating member may be of any suitable character and is here shown as an annular member 12 mounted for rotatory movement on the under- 30 side of the table top. This annular member may take various forms but, in the present instance, it is shown as a flat annular bar or ring arranged edgewise with relation to the table top, and slidably mounted in a series 35 of guides 13 which are rigidly secured to the table top. In the present construction each guide comprises a substantially U-shaped clip rigidly secured at its upper end to the table top and of such a size as to receive and slid- 40 ably support the annular actuating member. If desired, a washer 14 may be mounted about the upper portion of the clip so as to lie between the upper portion of the ring and the table top. Each leg is connected with the 45 actuating member by means of a connecting member or bar 15 which is pivotally connected with the leg at a point spaced from the axis thereof and, in the present instance, is mounted on the screw 16 by means of which 50 the brace bar 8 is secured to the leg. The other end of the connecting bar is so attached to the actuating member that the movement of the leg will move the actuating member about its axis, that is, cause it to slide in the 55 several guides 13. Preferably the actuating member or ring 12 is provided with a series of outwardly extending radial studs 17, there being one of these studs for each leg, and the adjacent end of each connecting bar is aper- 60 tured to receive one of these studs. The connection between the bar and the stud is a loose one so that the stud may be moved into different positions, by the movement of the actuating member about its axis, without dis- 65 torting the bar or causing the same to bind on

the stud. As here shown, the aperture, 18, in the connecting bar is of a greater diameter than the stud but the diameter of this aperture is such that when the leg has been moved to its extended position and the connecting 70 bar extends at an acute angle to the stud, the edges of the aperture will engage the opposite sides of the stud and thus hold the bar rigidly against longitudinal movement with relation thereto, and, consequently, hold the 75 leg against any movement with relation to the actuating member. In the present instance, the stud is provided with a head 19 and a spring 20 is mounted on the stud between the end of the bar and the actuating 80 member to move the bar outwardly toward the head.

Means are provided for locking the actuating member against reverse movement when the legs are in their extended positions and 85 thus causing the legs to be held rigidly in their extended positions. In the present device, a stud 21 is rigidly secured to the inner face of one of the flanges 2 and an apertured resilient arm 22 is secured at one end to the outer surface of the annular actuating member and so arranged that as the actuating member rotates to move the legs to their extended positions the arm 22 will engage and ride over the stud 21 until the aperture there- 90 in is brought into line with the stud, when the arm will spring outwardly and embrace the stud just as the legs reach the limit of their movement, thus rigidly holding the legs in their extended positions and locking the 95 same against movement in either direction. When the legs are to be folded the arm 22 is pressed inwardly to disconnect the same from the stud 21 and thus permit the reverse movement of the actuating member. As here 100 shown, the free end 23 of the locking arm constitutes a finger piece by means of which the arm may be manipulated to release it from the stud.

The tops of tables of this kind are usually 105 made of light material which has a tendency to warp or buckle and in order to reinforce the table top so as to prevent this warping or buckling I have secured to the underside of the table top two intersecting brace bars 24 110 which are rigidly secured to the table top preferably by nailing and gluing. The bars are of a length greater than the diameter of the annular actuating member and each bar is provided at each end with a transverse re- 115 cess or guideway 25 to receive the actuating member. In the present instance, the clips 13 extend into the recesses in the bars and form metallic linings for the same. It will be obvious, however, that if the bar is rigidly 120 secured to the table top it is unnecessary for the metallic lining to be also secured to the table top and the recessed ends of the bars may constitute the guides for the annular actuat- 125 ing member. The number of guides em- 130

ployed depends in a considerable measure upon the rigidity of the actuating member and if this member is sufficiently stiff four guides will be ample.

5. While I have shown and described one embodiment of my invention I wish it to be understood that I do not desire to be limited to the details thereof as various modifications may occur to a person skilled in the art.
10. Having now fully described my invention, what I claim as new and desire to secure by Letters Patent, is:

1. In a table, a table top, legs pivotally mounted on said table top, an annular member rotatably mounted beneath said table top, means spaced from the axis of said annular member to rotatably support the same and means for connecting said annular member with the several legs to cause said legs to 20 move in unison.

2. In a table, a table top, legs pivotally mounted on said table top, an annular member rotatably mounted beneath said table top, means spaced from the axis of said annular member to rotatably support the same and connecting bars for separately connecting the respective legs with said annular member.

3. In a table, a table top, legs pivotally mounted on said table top, an annular member 30 rotatably mounted beneath said table top, means spaced from the axis of said annular member to rotatably support the same, studs carried by said annular member, and separate bars connecting the respective legs with said studs.

4. In a table, a table top, legs pivotally mounted on said table top, an annular member rotatably mounted beneath said table top, means spaced from the axis of said annular member to rotatably support the same, studs carried by said annular member, and a plurality of bars each pivotally connected at one end with one of said legs and having its other end mounted on one of said studs for movement lengthwise of said stud.

5. In a table, a table top, legs pivotally mounted on said table top, an annular member rotatably mounted beneath said table top, studs carried by said annular member, and a plurality of bars each pivotally connected at one end with one of said legs and having at its other end an opening to receive one of said studs and loosely connect said bar therewith, said opening being of such a diameter 55 with relation to said stud that when said bar extends at an acute angle to said stud the edges of said opening will grip the stud.

6. In a table, a table top, legs pivotally mounted on said table top, an annular member rotatably mounted beneath said table top, studs carried by said annular member, a plurality of bars each pivotally connected at one end with one of said legs and having at its other end an opening to receive one of said studs and loosely connect said bar therewith,

said opening being of such a diameter with relation to said stud that when said bar extends at an acute angle to said stud the edges of said opening will grip the stud, and a spring acting on said bar to press the same 70 toward the outer end of said stud.

7. In a table, a table top, legs pivotally mounted on said table top, an annular member rotatably mounted beneath said table top, means spaced from the axis of said annular member to rotatably support the same, means for connecting said annular member with the several legs to cause said legs to move in unison, and means for locking said annular member in a position to hold said legs in their 80 extended positions.

8. In a table, a table top, legs pivotally mounted on said table top, an annular member rotatably mounted beneath said table top, means spaced from the axis of said annular member to rotatably support the same, means for connecting said annular member with the several legs to cause said legs to move in unison, a stud carried by said table top, and a yieldable locking member carried by said annular member and having an opening arranged to receive said stud when said legs are in their extended positions.

9. In a table, a table top, legs pivotally mounted on said table top, a series of guides 95 mounted beneath said table top, an actuating member mounted in said guides for rotatory movement in a plane substantially parallel with said table top and supported solely by said guides, operative connections between said actuating member and the respective legs, and cooperating locking members carried by said table top and said actuating member respectively, one of said locking members being yieldable to permit it to 100 spring into locking engagement with the other locking member when said legs have been moved to their extended positions.

10. In a table, a table top, legs pivotally mounted on said table top, a circular series of 110 guides secured to the lower side of said table top, a rigid ring slidably mounted in said guides, and operative connections between said ring and the respective legs.

11. In a table, a table top, legs pivotally mounted on said table top, a circular series 115 of guides secured to the lower side of said table top, a rigid ring slidably mounted in said guides, a plurality of studs carried by said ring, and bars pivotally mounted on the 120 respective studs and connected with said legs.

12. In a table, a table top, legs pivotally mounted on said table top, a series of guides mounted beneath said table top, an actuating member mounted in said guides for rotatory movement in a plane substantially parallel with said table top, and supported solely by said guides, and operative connections between said actuating member and the respective legs.

13. In a table, a table top, legs pivotally mounted on said table top, an actuating member mounted beneath said table top for rotatory movement in a plane substantially parallel with said table top, guides mounted at points remote from the axis of said actuating member and constituting the sole support for said actuating member, and operative connections between said actuating member and the respective legs.
14. In a table, a table top, legs pivotally mounted on said table top, a circular series of guides secured to the lower side of said table top, an actuating member mounted in said guides for rotatory movement in a plane substantially parallel with the plane of said table top, and operative connections between said actuating member and the respective legs.
15. In a table, a table top, legs pivotally mounted on said table top, reinforcing bars rigidly secured to the underside of said table top and each having recesses formed in that side thereof adjacent to said table top, an actuating member rotatably mounted in said recesses, and operative connections between said actuating member and said legs.
16. In a table, a table top, legs pivotally mounted on said table top, reinforcing bars rigidly secured to the lower surface of said table top and each having a series of guideways, the several guideways being arranged in a circle, a metallic ring mounted in said guideways, and operative connections between said ring and the several legs.
17. In a table, the combination with a table top having flanges depending from the edges thereof, of a leg, a brace bar secured to said leg and having its upper end spaced therefrom, a pin extending through said leg and the upper end of said brace bar, one of said flanges having a socket to receive one end of said pin, a bracket having an aperture to receive the other end of said pin, and means for securing said table top to another of said flanges after the several parts of said unit have been assembled and the end of said pin inserted in said socket.
18. In a table, a table top, a bracket having an apertured ear, a leg having an aperture near the upper end thereof, a brace secured to said leg at a point below said aperture and having its upper end spaced from said leg and provided with an aperture in line with the aperture in said leg, a pin having its end portions reduced, one of the reduced end portions of said pin being adapted to extend through and beyond said leg and the other reduced end of said pin being adapted to extend through said brace and the apertured ear of said bracket, whereby said parts may be assembled as a unit independently of said table top, a part carried by said table top and having a socket to receive the first mentioned end of said pin, and means for rigidly securing said bracket to said table top after said pin has been inserted in said socket.
- In testimony whereof, I affix my signature hereto.

GEORGE F. WILLETT.
